[57] ABSTRACT

A grenade for use in dispensing a vaporized explosive mixture in the atmosphere of a winding tunnel and igniting the mixture. The grenade provides a storage compartment for the pressurized explosive mixture and a separate compartment for elements of a delay ignitor. An operating mechanism, releases the pressurized mixture and actuates the delay ignitor for setting off the explosion of the vaporized mixture.

PATENTED JAN 22 1974

3,786,756

GASEOUS GRENADE

BACKGROUND OF THE INVENTION

This invention relates to the field of grenades. Explosion effects from conventional hand grenades are ineffective when used in winding tunnels because the winding tunnel localizes the explosion. Many underground tunnels have turns of 90° or more and follow winding paths which limit or localize the use of a hand grenade from widespread explosive effect in such tunnels.

SUMMARY OF THE INVENTION

This invention has provided a solution to such a problem by the use of a gaseous or pressurized fluid grenade. When actuated a pressurized explosive mixture is released into the atmosphere of a tunnel. After a predetermined time delay this mixture is ignited thereby causing a widespread explosive effect in the tunnel.

This invention may be better understood from the following detailed description taken in conjunction with the accompanying drawing.

BRIEF DESCRIPTION OF THE DRAWING

The single FIGURE shown is a sectional view of the gaseous grenade.

DESCRIPTION OF THE PREFERRED EMBODIMENT

Reference numeral 10 shows a typical aerosol container storing an explosive mixture 12, such as propane, in a pressurized condition. The container is provided with a spout 14 which is beaded at 16 for breakaway purposes. The upper end of the spout is closed off by one end of a handle 18 that is connected thereto. The

handle is withheld from inadvertent operation by a safety pin 20. The other end of the handle is connected to a delay ignitor generally indicated as 22 and is housed in compartment 23. A wire 24 extends through 5 a plug 25 and connects the handle to a sensitive ignitor mix 26 which is lit off by merely pulling the wire 24. The lighting of mix 26 will actuate a delay train 28 to then cause a flash mix 30 to produce a spark that sets off the vaporized explosive propane and explosion occurs. The period of time from lighting mix 26 to 10 sparking of flash mix 30 is predetermined to allow all the mixture 12 to be expelled from the container.

In operation, the safety pin 20 is removed and handle 18 is lifted up to break the spout at bead 16 and to start 15 the ignitor mix 26. By the time the mixture has been dispensed from the container a spark from flash mix 30 will set off the vaporized explosive.

I claim:

1. A grenade for dispensing a vaporized explosive mixture and for igniting the mixture, said grenade comprising: a container provided with a pressurized explosive mixture; a spout providing a discharge path for said pressurized mixture; a frangible seal for closing said spout; a delay ignitor supported by said container, and 20 operating means for breaking said seal to allow dispensing of said mixture and for igniting said delay ignitor to cause explosion of said dispensed vaporized mixture, said operating means including a handle having one 25 end connected to said frangible seal and the opposite end connected to said delay ignitor.

2. A grenade as set forth in claim 1 that includes a safety pin for preventing inadvertent operation of said handle.

UNITED STATES PATENT OFFICE
CERTIFICATE OF CORRECTION

Patent No. 3,786,756 Dated January 22, 1974

Inventor(s) LONNIE L. LOOGER

It is certified that error appears in the above-identified patent
and that said Letters Patent are hereby corrected as shown below:

On the cover sheet, insert -- [73] Assignee:
The United States of America as represented by the Secretary
of the Army -- .

Signed and sealed this 6th day of August 1974.
